UNITED STATES PATENT OFFICE

2,416,031

CENTRIFUGAL PUMP

John B. Wade, Hamilton, Ohio, assignor, by
mesne assignments, to Food Machinery Corporation,
a corporation

Application January 31, 1942, Serial No. 429,097

3 Claims. (Cl. 103—113)

1

This invention relates to improvements in centrifugal pumps and particularly to such pumps as are employed for pumping liquids having occluded vapor, or air or other gases.

When a centrifugal pump is operating under such conditions it is necessary to separate the occluded vapor and gases from the liquid before the latter is admitted to the pump or the vapor and gases will accumulate and pocket within the admission chamber of the pump forming a so-called vapor or gas lock which materially interferes with the proper operation of the pump.

Heretofore it has been the practice to build pumps intended for operating under such conditions as an integral part of the tank containing the liquid to be pumped, the pump being a part of the tank bottom. A vortex in the liquid was then produced and maintained by mounting the pipe introducing the liquid into the tank tangentially. I have observed that the cost of manufacturing pumps operating on this general plan for handling liquids with occluded vapors and gases is relatively high.

It is an object of my invention to produce a relatively inexpensive pump unit for pumping liquids having occluded vapors and gases.

It is another object of my invention to provide such a pump unit which is separate from the tank containing the liquid and therefore suitable for installation or removal without disturbing the tank installation.

It is a further object of my invention to provide a pump unit as aforesaid which may be inserted into a tank and suspended from above therein so as to operate near the bottom of the tank to pump liquid from the tank and separate occluded vapors and gases from the liquid before the latter is admitted to the pump.

It is a still further object of the present invention to provide a novel and efficient device for separating occluded vapors and gases from a liquid during the delivery of the latter to the impeller of a centrifugal pump.

The manner of accomplishing the foregoing objects as well as further objects and advantages will be made apparent in the following description taken in connection with the accompanying drawing, in which:

Fig. 1 is a vertical sectional view of a tank having a preferred embodiment of the invention installed therein.

Fig. 2 is an enlarged detail sectional view of the pump per se.

Fig. 3 is a horizontal sectional view taken on the line 3—3 of Fig. 2.

2

Fig. 4 is a horizontal sectional view taken on the line 4—4 of Fig. 2.

Referring specifically to the drawings, my invention is there shown as embodied in a pump unit 10 which is mounted in a tank 11 for the purpose of separating occluded vapors and gases from liquid contained in said tank and pumping said liquid from the tank. The unit 10 may include a motor base 12 supported on the tank 11 about an opening 13 in an upper wall thereof. The base 12 may support a motor 14 having a shaft 15 which is connected by a coupling 16 to a line shaft 17, a bearing 18 for which is preferably provided in the motor base 12.

Secured at its upper end to the motor base 12 is a heavy stationary tubing 20 which extends downwardly into the tank 11 and is connected at its lower end to a centrifugal pump 21 so as to suspend said pump on said tubing.

The pump 21 includes a casing 25 which may be formed of two parts as shown to provide an impeller chamber 26 there being an impeller bearing 27 formed centrally in the bottom of said casing. The chamber 26 is enlarged at one side 25 as shown in Fig. 4 to provide a discharge port 28 which leads to a threaded opening 29 into which the lower end of a liquid discharge pipe 30 may be screwed downwardly.

The impeller chamber 26 has a central bore 35 which extends upwardly through the upper half of the casing 25. Formed on the casing 25 about the upper end of the bore 35 is an annular collar 36 having a curved upwardly disposed surface 37 as shown in cross section in Fig. 2. Formed integral with the casing collar 36 and extending upwardly substantially vertically therefrom in circumferentially spaced relation is a series of struts 38.

These struts must be sufficiently strong to support the pump 21 and they have the added function of directing liquid through openings 40 formed therebetween into an admission chamber 41 which is disposed centrally in communication with the bore 35 and surrounded by the struts 38.

The preferred cross sectional contour of the struts 38 and the radially-opening passages 40 disposed therebetween is shown in Fig. 3. In this preferred contour the struts 38 are substantially "tear drop" in cross section with the bulk of their mass disposed outwardly adjacent the outer edge of the collar 36. The inner edges of the struts 38 are seen to be relatively sharp and as being formed by outwardly disposed concave side faces 45 and inwardly disposed convex side faces 46, these faces coming together at inner thin

edges of the struts so as to be substantially tangent with the outer limits of the admission chamber 41.

It may readily be seen that the formation and disposition of the struts 38 as clearly shown in Figs. 2 and 3 results in imparting a swirling motion to liquid entering the admission chamber 41 through the passages 40. It may also be noted that while planes passing through the outer and inner edges of the struts 38 are disposed spirally in a clock-wise direction as seen in Fig. 3, the bulk of the material in the struts 38 is preferably disposed between radial planes tangent with the side boundaries of the thickest portions of the struts. Viewed in this manner the inner portions of the struts 38 are seen to be turned in a clock-wise direction from the balance of the material in the struts.

The upper ends of the struts 38 are integral with a bonnet 50 having a bearing 51 and which is connected by cap screws 52 to the lower end of the tubing 20. The bottom face 53 of the bonnet 50 is preferably a shallow inverted conical surface which provides a ready escape for coalesced bubbles of vapor or gas separated from liquid in the admission chamber 41.

Rotatably mounted in the impeller chamber 26 is an impeller 60 having a stud 61 extending axially downwardly therefrom into the bearing 27. The shaft 17 extends downwardly through the bearings 18 and 51 and is connected axially with the impeller 60.

The construction of the impeller 60 follows conventional design and includes the formation of spiral passages 62 which lead from a central liquid admission throat 63 downwardly and outwardly to the periphery of the impeller. As clearly shown in Figs. 1 and 2 the throat 63 is formed in a neck 64 rotating in the bore 35. It opens upwardly directly into the admission chamber 41 and the upper end of this throat expands in diameter so that its surface is contiguous to and tangent with the adjacent curved surface 37 of the casing collar 36.

The discharge pipe 30 extends upwardly through a suitable opening in the motor base 12 so that the entire unit 10 may be mounted in the tank 11 as shown, without requiring the tank to be taken out of the ground or the making of any alterations on the bottom of the tank whatsoever.

Operation

After the unit 10 has thus been installed and liquid in which vapor or gas is occluded is delivered into the tank 11 to cover the pump 21, the motor 14 is energized to rotate the shaft 17 and impeller 60. Rotation of the impeller sucks liquid in through the passages 40, the admission chamber 41, the impeller throat 63 and expels this liquid from the impeller through the spiral passages 62. This liquid is thus forced upwardly through the port 28 and discharge pipe 30 and conducted by the latter to the place where it is desired this be delivered.

After the liquid is thus sucked inwardly through the passages 40 it is given an extremely rapid and smooth rotational movement as it enters the admission chamber 41. In this manner all of the liquid thus admitted is immediately subjected to a vortical action which separates the vapors and gases and permits these to escape upwardly along the bonnet bottom 53 in large bubbles which then rise to the surface of the liquid in the tank 11.

Having described the invention, I claim:

1. A vapor eliminating centrifugal pump comprising: an impeller casing; an impeller rotatable on a vertical axis therein, said impeller having a liquid admission throat opening axially upwardly; a vertical shaft connecting axially with said impeller; a plurality of substantially vertical struts provided on said casing and extending upwardly therefrom; and a bonnet vertically superimposed above the portion of said casing with which said struts connect, said bonnet being united with the upper ends of said struts, inner edges of said struts being relatively thin and contiguous with an admission chamber superimposed above and communicating with said throat, side faces of said struts in the direction of rotation of said impeller being concave and opposite side faces thereof convex, said side faces where they meet at the inner edges of said struts being substantially tangential with the outer limits of said chamber.

2. A vapor eliminating centrifugal pump comprising: an impeller casing; an impeller rotatable on a vertical axis therein, said impeller having a liquid admission throat opening axially upwardly; a vertical shaft connecting axially with said impeller; a plurality of substantially vertical struts provided on said casing and extending upwardly therefrom; and a bonnet vertically superimposed above the portion of said casing with which said struts connect, said bonnet being united with the upper ends of said struts, said struts being tear-drop in cross section with the bulk thereof disposed adjacent their outer edges and with their inner thinner edge portions inclined from the balance thereof in the direction of rotation of said impeller.

3. In a centrifugal pump the combination of: an impeller casing; an impeller rotatable on a vertical axis therein, said impeller having a liquid admission throat opening axially upwardly; a shaft extending downwardly through said throat to said impeller for rotating the latter; a bonnet surrounding said shaft and vertically superposed above said casing; and a plurality of struts spaced circumferentially about and radially from said shaft to define an admission chamber just above and opening downwardly into said throat, said struts uniting said casing with said bonnet, each of said struts having a comma-like cross section with the tail thereof contiguous with said admission chamber and turned in the direction traveled by the adjacent surface of said shaft.
